Primary Examiner — Karen S Acker

(57) CLAIM

The ornamental design for a pet car seat cover and pet barrier combination, as shown and described.

DESCRIPTION

FIG. 1 is a front, right, top perspective view of a pet car seat cover and pet barrier combination showing my new design; FIG. 2 is a front, left, bottom perspective view thereof; FIG. 3 is a back, left, top perspective view thereof; FIG. 4 is an enlarged front view thereof; FIG. 5 is an enlarged back view thereof; FIG. 6 is an enlarged left view thereof; FIG. 7 is an enlarged right view thereof; FIG. 8 is a top view thereof; and, FIG. 9 is a bottom view thereof.

The broken lines shown on the drawings depict portions of the pet car seat cover and pet barrier combination that form no part of the claimed design.
